UNITED STATES PATENT OFFICE.

WEST DODD, OF DES MOINES, IOWA.

MEANS FOR PROTECTING CONTENTS OF OIL-CONTAINING TANKS AGAINST IGNITION BY ELECTRICAL DISCHARGE.

1,155,648.

Specification of Letters Patent.

Patented Oct. 5, 1915.

Application filed November 5, 1913. Serial No. 799,279.

To all whom it may concern:

Be it known that I, WEST Dodd, a citizen of the United States, residing at Des Moines, in the county of Polk and State of Iowa, have invented certain new and useful Improvements in Means for Protecting Contents of Oil-Containing Tanks Against Ignition by Electrical Discharge, of which the following is a specification.

One of the objects of my invention is to protect the contents of storage tanks, powder magazines, and other like receptacles from destruction by electrical discharge.

I accomplish the object sought by surrounding the receptacle with a complete inclosing envelop, or housing, of electrically conducting material and by extending the housing, or covering, below the surface of the ground upon which the receptacle is located, and I furthermore electrically connect the receptacle, at suitable intervals, to the outside protecting envelop.

In carrying my invention into effect I place the envelop sufficiently far removed from the receptacle to be without the danger zone of ignition of the inflammable gases, or other explosive media, that emanate from and which usually surround such receptacles.

In the accompanying drawing Figure 1 is a plan view of an oil storage tank showing it surrounded with my protecting envelop, or cage. Fig. 2 is a central vertical section of same. Fig. 3 is an enlarged detailed view of one of the vertically projecting rods or points adapted to disperse the direct lightning charge. Fig. 4 is an enlarged sectional view of the portion of the tank, as shown broken away at the lower right hand corner of Fig. 2.

In all the views the same reference characters are employed to indicate similar parts.

In industrial oil fields, large numbers of tanks are usually connected together by oil conducting pipes, and the tanks of each group are similarly connected to tanks of a like group and these groups may be located at remote points, with respect to each other.

The intermediate conducting pipes are usually placed underground, and in their ramifications they are distributed throughout large territories. They therefore afford large and extended surfaces, as conducting mediums, over which electrical oscillatory

impulses may be propagated. The sudden and rapid rise and fall of potential, which is the physical manifestation of electrical oscillation, primarily due to an abrupt discharge within the inductive field of the conductor over which the oscillatory impulses pass, may inductively affect other electrical conductors within the field of the conductor upon which they are impressed and frequently abrupt discharges, characterized as sparks which are of much smaller significance than the primary discharge, are thus induced by the conductor of the first order in a neighboring conductor of the second order.

When a tank-containing inflammable oil,—or any isolated body of electrical conducting material, within ignition distance, is inductively affected by the supercharged pipes, atmosphere or ground, a spark may, and in the natural order of things will be produced between the charged and uncharged bodies. The spark thus produced may be ever so small, but when it occurs in the midst of a volume of explosive gases, experience has demonstrated that it will be of sufficient importance to ignite the gases and destroy the contents of the receptacle from which the gases may emanate.

Electrical oscillations, originating from abrupt electrical discharges between proximate clouds, or between clouds and the earth's surface, may be propagated through the ethereal or gaseous media of the atmosphere, or through the earth, and cause electrical undulations in the body of the storage receptacle and consequent sparks on its outside surface. Such "sparks" being manifested frequently as oscillatory discharges, or gradually dying away "brush" discharges. These discharges are always radiated from the outside surface of the mass or object from which they are projected, and therefore by electrically connecting the tank, or other receptacle, surrounded by my protecting means, with the protecting means itself, the igniting flame, brush, or spark, will not be made upon the receptacle but will occur upon the outside surface of the inclosing envelop, or cage, which is fully beyond the danger zone surrounding such receptacle.

In carrying my invention into effect with a storage tank of 100 feet in diameter I preferably leave an annular space of about ten

feet between the outside surface of the tank and the vertical walls of the cage, within which space operators may freely pass around the tank. This removes the protecting device a sufficient distance from the outside edges of the tank or away from the danger zone immediately surrounding the tank, as the gases coming from the tank at this distance away will be sufficiently diluted as to be non-explosive.

In the illustrative embodiment 10 is the tank, 11 is the top, 12 and 13 are the conducting pipes for conducting oil or other inflammable material to and from the storage tank.

In constructing my protecting cage I first dig a trench about two or three feet deep around the tank and preferably, generally circular in form, and removed from the vertical walls of the storage tank about ten feet, or I make the cage of a diameter about twenty feet greater than that of the tank, and in the trench I bury a tube or pipe, 14, preferably gas pipe, and having at sufficiently frequent intervals T's 15, into which to screw vertically disposed rods or pipes 16. I connect each of the pipes 16, to the sides of the tank, as by means of an electrical conductor pipe 17. Near the top of the tank I prefer to place, between the respective vertically disposed rods, or tubes 16, horizontal tubes 18, similar in character to those buried in the ground to form a second ring around the tank. In the top of each of the tubes 16 I place a point 19, similar to points carried by lightning rods, for protection of the tank from any abrupt discharge that may otherwise come directly from the clouds. To the ring 18, and the vertical rods or tubes 16, I fix wire cloth fabric 20, and at proper points, in the vertical walls of the cage, I place doors 21, having fabric or other metallic covering, through which doors employees may enter for access to the tank. Across the top of the structure I place a wire cloth cover 22 supported on wire cables 23 that are connected, as shown in Fig. 1, across the structure to the various vertically disposed posts 16 at the points where the ring 18 and the posts join.

Below the surface of the ground I place

a wire fabric 22', somewhat heavier than the fabric 22, as it is subjected to more rapid deterioration from the acids, and electrolytic effects of the earth.

I connect the pipes 12 and 13 to the cage, as at 12' and 13' respectively so that the cage will be of the same electrical potential as the pipes.

An imperforate cage of sheet metal may be used instead of the metal fabric, with substantially equally good results. I prefer the reticulate covering, however, as it interposes less wind resistance and is therefore more stable and enduring.

While I have herein shown a single embodiment of my invention for the purpose of clear disclosure, it is evident that changes may be made within the spirit of the invention within the scope of the appended claims.

Having described my invention, what I claim is:—

1. A cage for protecting the contents of storage receptacles from ignition by electrical disturbances comprising a circumferentially continuous electrically conducting structure extending above and below the receptacle and spaced apart therefrom; electric conductors connecting said structure and receptacle at intervals, and an electrically conducting cover overlying said receptacle, electrically connected to said circumferential structure.

2. A cage for protecting the contents of storage receptacles from ignition by electrical disturbances comprising two electrically continuous parallel rings, one above and the other below said receptacle; a series of vertically disposed rods included between the rings at intervals and extending above the upper ring; walls, of electrically conducting material, extending between said rings, encompassing said receptacle and over the top thereof and electrical conductors connecting said receptacle with said protecting means.

In testimony whereof I hereunto set my hand in the presence of two witnesses.

WEST DODD.
